UNITED STATES PATENT OFFICE.

EDWIN M. MARTIN, OF CINCINNATI, OHIO.

DESIGN FOR A BANNER.

54,948.

Specification for Design.

Patented Apr. 20, 1920.

Application filed February 10, 1919. Serial No. 276,235. Term of patent 7 years.

To all whom it may concern:

Be it known that I, EDWIN M. MARTIN, a citizen of the United States, residing at Cincinnati, in the county of Hamilton and State of Ohio, have invented a new, original, and ornamental Design for a Banner, of which the following is a specification, reference being had to the accompanying drawings, forming a part thereof.

The view is an elevation of a banner showing my new design.

I claim:

The ornamental design for a banner, as shown.

EDWIN M. MARTIN.
